AIR OPERATED IMPACT PRESS

Ray W. Bryant, Jackson, Mich., assignor to Air Hydraulics, Inc., Jackson, Mich., a corporation of Michigan

Application December 23, 1947, Serial No. 793,544

1 Claim. (Cl. 121—38)

1

This invention relates to pneumatic power impact press, hammer, riveter, die or the like machines of the kind which comprise a pneumatic cylinder and piston operated by the air pressure and carrying the operating part by which the desired impact action is applied.

It is an object of the present invention to provide an improved yet simple construction of pneumatic impact power press or the like of the above character which is highly efficient and is capable of operating with an extremely high impact characteristic.

It is a further object of the invention to provide a pneumatic impact power press, hammer, riveter or the like in which the required impact action is obtained with the use of a reservoir in which the energy of a body of compressed air is always stored-up ready for use, as and when desired, by the actuation of a simple release valve means which permits this body of pressure air to exert an explosive-like action upon the impact producing member, either directly or indirectly.

The apparatus in accordance with the invention therefor is distinguishable from known pneumatically actuated impact power presses which depend upon air pressure continuously supplied through a port to produce the desired impact motion since, with the apparatus provided by this invention, it is the stored up energy always present in the said reservoir which is utilized to produce each impact action.

The above and other objects and advantages of the invention will appear clear from a consideration of the following description with reference to one embodiment of the invention as illustrated in the accompanying drawings in which:

Fig. I is a longitudinal section of one embodiment of the invention, with the piston set for a power stroke.

Fig. II is an elevational view of Fig. I.

Fig. III is a section on the line III—III of Fig. II, and

Fig. IV is a section on the line IV—IV of Fig. III.

In carrying the invention into effect in one convenient manner as illustrated in the drawings pneumatic apparatus is provided, comprising a cylinder 1 having a head plate 2 and a base plate 3 and housing a double acting piston 4, connected with a plunger rod 5 which is of larger diameter than another plunger rod 6, which plunger rods are mounted for reciprocation through openings in the head plate and the base plate. The one plunger rod 6 serves for the

2

attachment at its lower end of a hammer head, riveting head, die or other part, the operation of which it is desired should take place with a hammer-like action under the influence of the pneumatic energy employed.

The differential diameters of the plunger rods result in the piston presenting differential annular piston surfaces on its opposite faces, of which the annular piston surface 7 presents a smaller surface area than the annular piston surface 8, which presents the largest surface area.

The head plate 4 has a port 9 to which a pipe connection 10 may be made for admitting pressure air to the cylinder space 11 enclosed between the smaller piston surface 7 and the head plate 4, whereas the base plate 3 also has a port 12 for admitting the pressure air to the cylinder space 13 enclosed between the larger piston surface 8 and the base plate 3.

The pressure air to both cylinder spaces is supplied from a common source, as from an air compressor, and is conveniently distributed to the two cylinder spaces through a pipe hook-up consisting of the T 14, connection 10 and the pipe 15, the T being itself connected to the compressor, and the pipe 15 conducting the pressure air from the T to a port 16 (Figs. II and III) in the base plate 3, which port 16, and also a laterally adjacent and spaced port 17, are under the control of a piston valve 18.

This piston valve is reciprocable within a hollow cylindrical portion 19 formed in the base plate 3 and divides such cylindrical portion into two cylinder spaces 20 and 21, of which the space 20, in the position of the piston valve 18 as seen in Fig. III, connects the port 16 with an extension 22 of the cylindrical space 20, which extension is open to the port 12. The other cylinder space 21 contains the port 17 by which pressure medium (normally compressed air) can be introduced into this cylinder space under the control of a multi or three way pilot valve 39, shown diagrammatically in Fig. II. Also the piston 18, constituted by a sealing ring 23 located in an annular space formed between axially spaced flanges 24, has a reduced piston portion 25 connected with an axially spaced head 26 by means of an intermediate connecting shank 27 of spider formation as shown in Fig. I in particular, this connecting shank being formed by axially extending radial webs or fins 28 which afford a clear passageway between them for the flow of the pressure air between the ports 16 and 12. The head 26 is reciprocable within a cylin-

der space 29 containing an exhaust port 30. Both the reduced piston portion 25 and the head 26 are fitted with sealing rings 31 and 32 respectively for maintaining sealing contact with the opposed annular end wall surfaces 33 of their respective cylinder spaces.

The piston 4 is also conveniently formed by a pair of axially spaced flanges 34 forming an annular space between them in which a sealing or O ring 35 is located. The plunger rods 5 and 6 may also operate past sealing or O rings 36 in their respective end bearing plates 2 and 3.

A coil spring 37 mounted about the plunger rod 5 and bearing at one end against the piston face 7 and at the opposite end against the inside surface of the end plate 2 serves to maintain the piston 4 normally in predetermined spaced relationship from the end plate 2, whereby to provide that the cylinder space 11 is of a certain normal area or size.

Another coil spring 38 mounted about the plunger rod 6 and bearing at one end against the inside surface of the base plate 3 serves as a buffer or cushion spring.

With the construction as thus described and as shown in the drawings, pressure air can be admitted from the common supply source (normally an air compressor) into the two cylinder spaces 11 and 13, the passage of the pressure air into the cylinder space 13 being possible due to the fact that the piston valve 18 is shown positioned to leave the port 16 open to the cylinder spaces 20, 22 and hence to the port 12. The differential areas of the piston surfaces 7 and 8 provide that in this condition of the piston valve 18 and its connected parts, the piston 8 is held in a raised position, as shown in Fig. I, against the action of the coil spring 37, the latter acting merely as a spacer to cause a measured space or area to exist above the piston 4, this space being constituted by the cylinder space 11 and being filled by the compressed air delivered through the port 9 at the same time as the cylinder space 13 is filled with the compressed air delivered through the ports 16 and 12.

With the apparatus thus set, in order to produce an operative stroke of the plunger rod 6, and thereby to produce the required hammer, riveting, or like impact action, the pilot valve 39 is adjusted to permit pressure air to enter the cylinder space 21 through the port 17 and thereby push the piston valve 18 to the left, as seen in Fig. III, to a position in which the port 16 is closed by the piston valve and the sealing ring 31 is in contact with the annular cylinder end wall 33. With the piston valve so set the supply of compressed air to the cylinder space 13 is cut off, while simultaneously therewith the packing 32 of the valve head 26 is unseated from the cylinder surface 33 and thus opens the cylinder space 13 to the outer atmosphere via the ports 12, cylinder extension 22 and exhaust port 30.

It may be pointed out here that the diameters of the ports 12 and 30, including also that of the cylinder extension 22, are relatively large and offer no resistance to the flow of the air, whereby upon the piston valve head 26 being moved to the open position the compressed air previously enclosed within this cylinder space 13 is exhausted in a flash. It should also be pointed out that the cylinder space 11 is always charged with a supply of the compressed air and accordingly, in the elevated condition of the piston 4, always has the energy of this body of compressed air stored-up therein. Accordingly, when the cylinder space

13 is exhausted this stored-up energy of the body of the compressed air within the enclosed cylinder space 11 operates with an explosive-like action upon the piston 4 and thereby causes the piston rod 6 to travel at high velocity and accelerated motion through the base plate 3 and results in the obtaining of an extremely high impact characteristic. The actual speed of operation can be regulated by the connection of a control valve with the exhaust outlet 30.

In the event that the desired operative impact is not effected beforehand, the arrival of the piston 4 at the coil spring 38 will permit this spring to come into effect to cushion the piston motion and thereby prevent undue damage by impact of the piston with the base plate 3.

To re-set the apparatus for another operative cycle the pilot valve 39 is adjusted to exhaust the air from the cylinder space 21 and thereby permit the pressure air at the inlet port 16 to push the piston valve 18 to the right, into the position shown in Fig. III, the piston valve head 26 being at the same time closed, as shown. In this position of the piston valve 18 and its head 26 the cylinder space 13 is filled with the compressed air and the piston 4 is ready for another power stroke.

It will be seen that with the existence of the differential piston surfaces 7 and 8 equal air pressure within the cylinder spaces 11 and 13 will result in the piston being held in a raised position as shown in Fig. I, both cylinder spaces being then filled with the pressure air. It will also be appreciated that the valve mechanism provided, that is, the pilot valve 39 and the piston valve 18 with its connected valve head 26, permits the cylinder space 13 to be alternatively exhausted and filled with air at the same high pressure as that in the cylinder space 11, which latter is at all times filled with the pressure air.

Having thus described my invention and one practical embodiment thereof, it being understood that other practical embodiments are possible, what I claim as novel is:

A pneumatic power impact machine tool comprising a cylinder having air line pressure connections at opposite ends, a piston in said cylinder for reciprocation therein by differential air pressure on opposite sides thereof, closure structure for the ends of said cylinder having apertures therein, rods of different diameter extending from opposite sides of said piston axially of said cylinder through said apertures to provide said cylinder with differential effective surface areas upon opposite sides thereof, a coiled compression spring embracing the rod of larger diameter and disposed between said piston and the closure structure for one end of said cylinder to space said piston from one end of said cylinder to provide a storage chamber for air pressure and to store up energy against the side of said piston of lesser effective area, a similar spring embracing said rod of smaller diameter to act as a buffer upon being engaged between said piston and the closure structure for said cylinder, conduit structure attached to said connections for simultaneously conducting air under said line pressure to said cylinder upon opposite sides of said piston to move said piston into a position compressing said spacing spring due to said differential effective surface areas, exhaust structure for the rapid removal of air pressure from the end of said cylinder in which said buffer spring is disposed, and valve means associated with said conduit 75 and exhaust structure for exhausting air from

one side of said piston only to enable the air pressure in that portion of the cylinder in which said spacing spring is located to rapidly expand and move said piston, aided by the stored energy of said spacing spring, to impart high velocity movement to said piston into engagement with said buffer spring, that portion of said conduit structure connecting with said storage space continuously connecting line air pressure with said storage space.
